(57) **CLAIM**

The ornamental design for a packaging container, as shown and described.

DESCRIPTION

FIG. 1 is a perspective view of a packaging container showing our new design;
 FIG. 2 is another perspective view thereof;
 FIG. 3 is another perspective view thereof;
 FIG. 4 is a front view thereof;
 FIG. 5 is a rear view thereof;
 FIG. 6 is a left side view thereof;
 FIG. 7 is a right side view thereof; and,
 FIG. 8 is a bottom views thereof, the top view being a mirror image.

The broken lines depict portions of the packaging container which form no part of the claimed design.

1 Claim, 8 Drawing Sheets
